B. H. SMITH

CONTROL SYSTEM

Filed Feb. 3, 1925

UNITED STATES PATENT OFFICE.

BENJAMIN H. SMITH, OF SWISSVALE, PENNSYLVANIA, ASSIGNOR TO WESTINGHOUSE ELECTRIC & MANUFACTURING COMPANY, A CORPORATION OF PENNSYLVANIA.

CONTROL SYSTEM.

Application filed February 3, 1925. Serial No. 6,536.

My invention relates to control systems and particularly to load control systems for systems of distribution.

One object of my invention is to provide a control system that shall have means for controlling auxiliary or stand-by generators to assume the peak loads where the average load on a system is supplied by a main source of supply.

10 Another object of my invention is to provide a control system for an auxiliary generator that functions in accordance with the varying load, such as a railway load, upon another source of supply which may be a relatively great distance away from the auxiliary machine.

20 Patent No. 1,199,571, to J. E. King, dated September 28, 1916, discloses a load-regulating system comprising a main generator and an auxiliary generator, the latter being controlled in such manner that it will assume all of the load on the system in excess of a certain value.

25 The present invention is an improvement upon the system disclosed in said patent and comprises a wattmeter connected in the main supply circuit that is adapted to control the auxiliary generator, the controlling means being unaffected by the distance separating the 30 main and auxiliary generators in case these machines are widely separated.

For a clear understanding of my invention, reference should be had to the accompanying drawings, wherein

35 Fig. 1 is a diagrammatic view of an alternating-current system embodying my invention, and

Fig. 2 is a similar view of a modification thereof.

40 Referring to Fig. 1, an alternating-current distribution system is shown comprising a main supply circuit 1, an auxiliary supply circuit 2 and a plurality of distribution circuits 3 connected to both of said supply circuits. A three-phase alternator 4 is connected to the main supply circuit and supplies power to the distribution circuits under normal conditions. A second three-phase alternator 5 is connected to the auxiliary supply circuit to supply the power to the system in excess of a predetermined value.

One application of my invention is in railway distribution systems in which the railway company purchases power from a sepa-

rate source of power and maintains an auxiliary or stand-by source of energy for emergency conditions. Since the cost of the purchased power is ordinarily based upon the maximum load demand, it is desirable to arrange the auxiliary source of power to be brought into operation automatically in case the load exceeds a predetermined value, thereby reducing the peak-load demand upon the main source.

In the accompanying drawings, the generator 4 is the main source of supply and the generator 5 is the auxiliary source. Since railway distribution systems are usually extensive, the auxiliary source 5 may be connected to the system at a point that is a relatively great distance away from the point of connection of the main source. Accordingly, if a control circuit is used for controlling the auxiliary source of power in accordance with the load on the main source, it is desirable to provide a transmission system that is not affected by the variations in resistance or the other characteristics of the control circuit.

The control system shown comprises an integrating wattmeter 6 connected to the main supply circuit 1 to measure the power supplied by the generator 4 to the distribution circuits 3. A control circuit 7 extends from the wattmeter 6 to a controlling device 8 associated with the auxiliary generator 5. The auxiliary generator 5 is driven by a prime mover 9, such as a water wheel or steam turbine. A governor 10 controls the speed of the prime mover 9, and a valve 11 controlled by a pilot motor 12 controls the supply of water or steam to the prime mover 9.

35 The wattmeter 6 is adapted to generate current impulses at a rate proportional to the power measured by the wattmeter, and a Kelvin balance 13 responsive to said current impulses controls the pilot motor 12 to regulate the load on the auxiliary generator 5.

45 The wattmeter 6 is of the usual motor or induction type and the rotating element thereof is provided with a commutator 14 controlling the circuit of an impulse relay 15. As the motor element of the wattmeter rotates, the circuit of the impulse relay 15 is alternately closed and broken at a rate that is proportional to the power traversing the main supply circuit 1. The impulse relay 15 controls an impulse relay 16 associated with the auxiliary generator over the control circuit 7. The

operation of the impulse relay 16 alternately charges a condenser 17 in opposite directions from a battery 18 through the windings of the Kelvin balance 13. Since the potential of the 5 battery 18 and the capacity of the condenser 17 are constant, the average current traversing the Kelvin balance 13 is proportional to the 10 rate of operation of the impulse relay 16 and, consequently, to the energy traversing the main supply circuit 1.

The movable element of the Kelvin balance 13 has a relatively large inertia and is highly damped so that the average torque is dependent upon the frequency of the current impulses even when they are impressed upon the 15 balance at a slow rate, such as only one impulse in two or three seconds.

Under normal conditions, the generator 4 supplies the power demand and the generator 20 5 is running idle. If the load demand increases above a certain value, the frequency of the 25 current impulses generated by the wattmeter 6 actuates the Kelvin balance 13 and controls the pilot motor 12 in such manner as to open the valve 11 and cause the generator 5 to assume the increment of load. When the 30 load decreases again, the frequency of the current impulses in the control circuit 7 is lessened and the Kelvin balance 13 actuates the pilot motor 12 to close the valve 11 and transfer the total load to the main generator 4. Since the operation of the Kelvin balance 13 is dependent solely upon the frequency of the 35 current impulses in the control circuit 7, the accuracy of the controlling operation is not affected by variations in the resistance of the control circuit and, therefore, the control may be exercised over relatively great distances.

40 In Fig. 2, I have shown a modification of my invention comprising a direct-current distribution system. A pilot motor 12 is controlled in accordance with the load on the main generator through the instrumentality 45 of the Kelvin balance 13 in the same manner as shown in Fig. 1. A direct-current auxiliary generator 19 connected to the distribution system is controlled by a field rheostat 20 actuated by the pilot motor 12. In case 50 the load increases above a predetermined value, the pilot motor 12 is actuated in such a direction as to decrease the resistance 20, thereby increasing the field excitation and causing the generator 19 to assume the increment of load.

I do not consider that my invention is limited to the precise embodiment shown and described, as it embraces the general conception of the remote control of a dynamo-electric machine in accordance with the load in a supply circuit. Accordingly, I do not wish my invention limited in scope except as indicated in the appended claims.

I claim as my invention:

65 1. A system comprising a main generator,

an auxiliary generator, a wattmeter associated with the main generator, a current-impulse sending device operated by the wattmeter, load-regulating means for the auxiliary generator and means including said 70 wattmeter and current-impulse device for controlling said load-regulating means.

2. A system comprising a supply circuit, a wattmeter connected therein, a current-impulse sending device operated by the wattmeter, a generator for supplying energy to the supply circuit, load-regulating means for the generator and means including said wattmeter and current-impulse device for controlling 75 said load-regulating means in accordance 80 with the load on said supply circuit.

3. A system comprising a supply circuit, a wattmeter connected therein, a dynamo-electric machine at a remote point from said wattmeter for supplying energy to the supply circuit, conductors extending from said wattmeter to said dynamo-electric machine, means for transmitting the indications of said wattmeter over said conductors, said means being unaffected by the resistance of said 85 conductors, and means connected to said conductors for controlling said machine in accordance with the power traversing said supply circuit.

4. A system comprising a main generator, an auxiliary generator at a relatively great distance therefrom, a control circuit between said generators, means for transmitting an indication of the load on said main generator over said circuit, said means being so arranged that the accuracy of transmission is unaffected by variations in the resistance of said circuit, and means responsive thereto for causing the auxiliary generator to assume all 90 load in excess of a certain value.

5. A system comprising a supply circuit, a second supply circuit, a wattmeter in the first-mentioned circuit, a generator connected to said second supply circuit, means for modifying a periodic controlling current at a rate 100 that depends upon the power measured by said wattmeter and means for controlling said generator in accordance with the periodicity of said controlling current.

6. A system comprising a supply circuit, a wattmeter connected thereto, means for generating current impulses at a rate depending upon the power measured by said wattmeter, a dynamo-electric machine for supplying energy to the supply circuit and means responsive to said current impulses for controlling said machine.

7. A system comprising a supply circuit, a second supply circuit, a wattmeter in the first-mentioned circuit, a generator connected to the second supply circuit, a control circuit connecting the wattmeter and the generator, means for producing a current in said control circuit in accordance with the power measured by said wattmeter, and means connected 120 125 130

to said control circuit for causing the generator to assume the increments of load on the system.

8. A system comprising a supply circuit, a 5 wattmeter connected thereto, means for generating current impulses at a rate depending upon the power measured by said wattmeter, a dynamo-electric machine for supplying energy to the supply circuit and means re-

sponsive to said current impulses for rendering said machine effective when the load on said supply circuit exceeds a predetermined value. 10

In testimony whereof, I have hereunto subscribed my name this 23rd day of January 15 1925.

BENJAMIN H. SMITH.
